Attorneys:

UNITED STATES PATENT OFFICE.

CARL GUSTAV MORGNER, OF CHICAGO, ILLINOIS.

SCREEN FOR PASSENGER-CARS.

1,071,565.

Specification of Letters Patent. Patented Aug. 26, 1913.

Application filed November 11, 1912. Serial No. 730,714.

To all whom it may concern:

Be it known that I, CARL GUSTAV MORGNER, a citizen of the United States, residing at Chicago, in the county of Cook and State 5 of Illinois, have invented certain new and useful Improvements in Screens for Passenger-Cars; and I do declare the following to be a full, clear, and exact description of the invention, such as will enable others skilled in the art to which it appertains to 10 make and use the same.

This invention relates to improvements in screens for passenger cars.

One object of the invention is to provide 15 a car screen having an improved construction and arrangement of guiding and retaining members whereby the screen is slidably supported in the window frame.

Another object is to provide means whereby 20 when not in use the screen may be readily pushed up to an out of the way position entirely above the window sash and means for yieldingly and removably holding the screen in place and preventing the 25 same from rattling.

With these and other objects in view, the invention consists of certain novel features of construction, and the combination and arrangement of parts as will be more fully 30 described and claimed.

In the accompanying drawings: Figure 1 is a vertical sectional view through a window frame showing my improved screen applied thereto and in an elevated or inoperative position; Fig. 2 is a similar view 35 taken through the center of the parting strips and screen guides of the window frame showing the screen in lowered or operative position. Fig. 3 is a vertical cross

40 sectional view taken on the line 3—3 of Fig. 2 with the screen in full lines. Fig. 4 is an enlarged horizontal sectional view through the window frame, sashes and the screen; Fig. 5 is an enlarged vertical sectional view 45 through the screen guiding shoes and through the outer portions of the screen frame, showing more particularly the construction and arrangement of the means for fastening the screen in place and the means 50 for locking the screen operating devices in their projected positions; Fig. 6 is a vertical cross sectional view through the upper bar of the screen frame showing more particularly the construction and arrangement of 55 the weather strip carried thereby; Fig. 7 is a detail side view of the left hand screen

guiding shoe, parts of the same being broken away and in section; Fig. 8 is an inner edge view thereof; Fig. 9 is an enlarged inner edge view of the upper portion of the left hand screen guiding shoe showing more particularly the screen fastening catch in the upper end thereof; Fig. 10 is a cross sectional view through the upper end of the left hand screen guiding shoe taken on the line 10—10 of Fig. 9. Fig. 11 is a side view of the inner side of the screen showing the operating rods thereof in a projected position; Fig. 12 is an enlarged vertical sectional view of the lower left hand corner 70 of the screen frame and the operating and plunger projecting rod for this side of the screen; Fig. 13 is a side view of the lower end of one of the screen operating rods and the lower end of the plunger projecting rod; 75 Fig. 14 is an outer edge view of the parts shown in Fig. 13; Fig. 15 is an outer edge view of a portion of the left hand side bar of the screen frame; Fig. 16 is a vertical cross sectional view through the lower bar 80 of the screen frame taken on the line 16—16 of Fig. 11. Fig. 17 is an enlarged vertical sectional view through the lower right hand corner of the window frame and through the spacing bar, parting strip and screen 85 guide of this side of the frame showing more particularly the manner in which the parting strip is fastened to the spacing bar and the manner in which the lower end of the screen guide is fastened to the parting 90 strip; Fig. 18 is a similar view of the lower end of the parting strip shown in Fig. 17; Fig. 19 is an irregular horizontal sectional view taken on the line 19—19 of Fig. 17; Fig. 20 is a detail perspective view of the 95 operating member which may be employed for raising and lowering the screen instead of the screen operating bars thereof.

My improved screen comprises a frame, the side, top and bottom bars of which consist of inner and outer members 1 and 2, which are preferably formed of metal strips bent into the desired shape. The inner members 1 of the screen frame are bent along their edges to form inner flanges 3 and outer flanges 4 which project at right angles to the face of the members and in the face of the members midway between said flanges is preferably formed an inwardly projecting reinforcing bead 5 which imparts 105 rigidity to the frame members 1. The outer flanges 3 of the frame members have their

edges turned or folded back to form ribs 6 the purpose of which will be hereinafter described. The flanges 4 of the outer edge of the members 1 are curved outwardly toward their outer edges for a purpose which will also be hereinafter described.

The outer members 2 of the screen frame have their inner edges bent inwardly at right angles to form gripping flanges 7 which incline inwardly to a slight extent and have their outer edges turned outwardly to a slight degree as shown. The outer edges of the members 2 are bent to form longitudinally disposed cylindrical tubes 8 which reinforce the frame members and also serve as casings for operating devices hereinafter described. In the faces of the members 2 of the screen are formed inwardly extending strengthening beads 9 which serve to reinforce this part of the members.

In assembling the inner and outer members of the screen frame the outwardly curved flanges 4 on the outer edges of the screen members 1 are engaged with the inner sides of the tubes 8 of the outer members while the edges of the inner flanges 3 having the ribs 6 are sprung into engagement with the inwardly projecting flanges 7 of the outer members 2 of the screen frame.

By constructing the inner and outer members of the screen frame as herein shown and described it will be seen that when said members are engaged in the manner described they will be securely fastened together and cannot be separated without the use of a proper tool and the application of considerable force.

Arranged in the frame of the screen is a covering 10 of fine mesh wire netting the edges of which are firmly gripped and fastened between the engaging inner and outer flanges of the members 1 and 2 of the screen. Secured to the tube 8 of the outer member 2 of the upper cross bar of the screen frame is a weather strip 11 formed of a piece of suitable fabric folded lengthwise and having its inner edges stitched together and inserted into the tube 8 of the upper cross bar of the screen frame between the free edge of the tube and the adjacent portion of the frame member 2. The folded outer edge of the weather strip projects a suitable distance beyond the outer side of the frame member 2 while the stitched inner edges project into the tube and have engaged therewith a retaining rod 12 as clearly shown in Fig. 6 of the drawings. The weather strip 11 when thus arranged will engage the adjacent part of the outer sash of the window and thus form an air tight engagement between the upper portion of the screen and the outer sash.

The screen frame is preferably braced by means of a vertically disposed tubular cen-

ter bar 13 which is arranged midway between the side bars of the frame and has its ends rigidly secured in any suitable manner to the inner flanges 7 of the outer screen members 2 of the upper and lower bars of the frame as shown. Detachably engaged with the right hand side bar of the screen frame is a right hand guide shoe 14 comprising a substantially U-shaped metal plate the sides of which have a close sliding engagement with the outer sides of the members 1 and 2 of the left hand side bar of the frame, while the loop shaped outer edge of the plate embraces the tube 8 of the outer member 2 of this side of the screen frame. The outer side of the shoe 14 is offset slightly as at 15 to closely fit the offset edge of the tube 8 as shown. The loop shaped outer edge of the shoe 14 has arranged therein one or more flat vertically disposed springs 16 which are adapted to engage the adjacent outer surface of the tube 8 of the member 2 of this side of the screen whereby the shoe 14 is yieldingly held in spaced relation to said tube and is held in yielding engagement with the right hand screen guiding member hereinafter described. On the upper end of the guide shoe 14 is a hook shaped lug 17 which is adapted to engage the outer end of the tube 8 of the upper cross bar of the screen frame thereby holding the shoe 14 in position on the screen frame.

Engaged with the left hand side bar of the screen is a left hand guide shoe 18 which comprises a channel shaped plate and is constructed in the same manner as the shoe 14 on the right hand side of the screen frame. The shoe 18 has its side members slidably engaged with the outer surface of the members 1 and 2 of the left hand side bar of the screen frame and is provided with a flat centrally disposed spring 19 and at its lower end is provided with a similar spring 20. The spring 20 is adapted to engage the lower end of the tube 8 of the outer member 2 of this side of the screen while the spring 19 is engaged by a shoe adjusting mechanism hereinafter described whereby the shoe 18 is spaced from the tube 8 and left hand side bar of the screen and held in yieldingly slidable engagement with the left hand screen guide. By thus arranging the shoe 18 and the spacing mechanism therefor on the left hand side of the screen frame and the guide shoe 14 on the right hand side thereof it will be seen that the screen frame may be held in operative position in window frames which vary slightly in width and may be readily removed from the window frame as will be hereinafter more fully described. The shoe 18 is held in sliding engagement with the upper end of the side bar of the screen by a guiding and retaining plate 21 which is soldered or otherwise rig-

idly secured at its inner end to the inner member of the upper cross bar of the screen frame and has at its upper edge a hook shaped flange 22 which engages the tube 8 on the upper cross bar of the frame. The outer portion of the guide plate 21 is offset from the adjacent outer surface of the side bar of the frame a sufficient distance to form a space with which the adjacent side of the shoe 18 is slidably engaged. In the offset end of the plate 21 is formed a channel 23 with which is engaged a short rib or bead 23' struck in or formed on the side of the shoe whereby the upper end of the latter is held in sliding engagement with the upper end of the screen frame. The lower end of the shoe 18 is provided with a frame engaging bail 24 the loop-shaped inner end of which is arranged at right angles to the side bars thereof and is adapted to engage beneath the tube 8 of the lower cross bar of the screen frame while the sides of the member 24 engage the opposite sides of said lower cross bar as clearly shown in the drawings. When thus arranged the bail shaped member 24 holds the lower end of the shoe 18 in sliding engagement with the lower left hand corner of the screen frame and together with the plate 21 holds said shoe against vertical movement on the screen frame but permits the latter to be readily adjusted laterally on the left hand side of the screen frame.

Secured in the upper end of the shoe 18 is a spring frame supporting catch 26 which corresponds with a similar catch 27 secured to the upper end of the tube 8 of the left hand side bar of the frame, said catches 26 and 27 having their upwardly projecting ends bent to form catch lugs 28 which are engaged with the screen guiding members hereinafter described to yieldingly hold the screen in closed and open positions.

The screen guiding members herein referred to comprise right and left hand channel shaped bars 29 and 30, having on their outer edges laterally extending gripping flanges 31. The bars 29 and 30 are detachably engaged with right and left hand tubular sash parting strips 32 and 33 which are arranged between the inner and outer sashes 34 and 35 of the window frame. The left hand parting strip 33 is riveted or otherwise rigidly secured to the left hand side of the window frame 36 which is herein shown as being formed of pressed sheet metal. The sashes 34 and 35 are slightly narrower than the width of the window frame and between said sashes and the right hand side of the window frame 36 which is herein shown as being formed of pressed sheet metal, are narrow spaces 37 with which are engaged springs 38 whereby the sashes are held against rattling. In thus constructing the sashes and window frame a space 39 is

formed between the right hand parting strip 32 and the side of the window frame and arranged in this space and riveted or otherwise secured to the adjacent side of the window frame is a spacing bar 40 to which the right hand parting strip 32 is detachably secured.

The parting strip 32 is detachably secured to the spacing bar 40 at its upper end by an elongated offset hook 41 which is preferably constructed and bent inwardly from the bar and is adapted to engage a slot 42 in the parting strip 32 near its upper end as shown. In the lower end of the parting strip is formed a rectangular notch 43 which is adapted to be engaged with a T-shaped lug 44 formed on the lower end of the spacing bar 40. The parting strip 32 is further secured to the bar 40 intermediate its ends by means of spring clips 45 which are secured to the inner side of the parting strip and have their lower ends projecting through slots 46 in the rear wall of the parting strip. The ends of the clips 45 after passing through the slots 46 extend downwardly and form catches 47 which are adapted to be sprung into engagement with slots 48 in the adjacent portion of the bar 40 as shown.

The inner ends of the spring clips 45 project upwardly and form catches with which are engaged hooks 49 secured to the inner side of the right hand screen guide 29 whereby said guide is detachably secured to the right hand parting strip. The left hand parting strip 30 has secured to its inner side, hooks 50 which correspond to the hooks 49 of the right hand screen guide and are adapted to be engaged with upwardly projecting hooks or clips 51 arranged on the inner side of the left hand parting strip 33 said clips or hooks 50 being preferably cut and struck inwardly from said parting strips as shown.

The parting strips 32 and 33 are in the form of hollow or tubular rectangular bars as herein shown, said bars having in their inner sides vertical passages with which the right and left hand screen guides are engaged when said guides are secured to the parting strips in the manner described.

Riveted or otherwise secured to the inner sides of the screen guides 29 and 30 are weather strips 51 the edges of which project beyond the offset side edges 31 of the screen guides and are clamped between said offset edges of the screen guides and the adjacent edges of the parting strips 32 and 33 as clearly shown in Fig. 4 of the drawings. The projecting edges of the weather strips when thus arranged and secured between the parting strips and screen guides engage the adjacent inner surfaces of the side bars of the inner and outer sash and form an air and dust tight connection between the sash and the parting strip.

The adjusting mechanism for the left hand guide shoe 18 of the screen frame hereinbefore referred to comprises a cam link 52 which is engaged with a vertical slot 53 in the outer side of the tube 8 on the outer member 2 of the left hand side bar of the screen. The inner end of the link 52 is pivotally secured to a plug 54 which is arranged in the tube 8 and riveted or otherwise secured thereto adjacent to the lower end of the slot 53 as shown. The outer end of the link 52 is rounded and when said link is swung downwardly to a horizontal position and projected laterally through the slot 53 and beyond the outer side of the tube 8, said rounded outer end will be brought into engagement with the spring 19 on the inner side of the shoe 18 and will yieldingly force said shoe outwardly into close sliding engagement with the left guide member 30 of the parting strip 33 thereby holding the screen in sliding engagement with the guide members on the parting strips of the window frames. When the link 52 is in an operative position as just described the screen will be held against removal from the screen guides and in order to permit the removal of the screen I provide means for retracting the link 52 into the tube 8 which will permit the screen frame to be slipped laterally in the shoe 18 a sufficient distance to permit the shoe 14 and opposite side of the screen to be disengaged from the right hand screen guide as will be readily understood.

The retracting mechanism for the cam link 52 comprises a link retracting rod 55 which is arranged in the upper portion of the tube 8 and has secured to its lower end a rod centering and guiding block 56 and to its upper end a cylindrical guiding and centering block 57 having in its upper end a threaded socket 58. The lower end of the rod 55 is pivotally connected to the inner end of a pair of retracting links 59 the outer ends of which are pivotally connected to the outer end of the cam link 52 whereby when the rod 55 is drawn upwardly in the tube 8 said links 59 will swing the link 52 upwardly thereby retracting the same into the tube and releasing the shoe 18 as herein-after described. The rod 55 is drawn upwardly in the tube 8 to retract the link 52 by means of an operating screw 60 which is revolvably mounted in a tubular bearing block 61 rigidly secured in the upper portion of the tube 8 and has its threaded lower end engaged with the threaded socket 58 in the block 57 secured to the upper end of the rod 55. The screw 60 is held in revolvable engagement with the block 61 by a collar 62 which is fastened on the screw by a rivet 63 or other suitable fastening means adjacent the inner end of the block 61 as shown. The head of the screw 60 when thus arranged is disposed adjacent to the upper end

of the tube 8 and is provided with a slot with which a screw driver may be engaged when inserted in the upper end of the tube and the screw 60 thus turned in the proper direction for drawing the rod 55 upwardly or pushing said rod downwardly to retract or project the link 52 as will be readily understood.

In order to permit the screen frame to be pushed upwardly to an inoperative position above the upper sash of the window frame I provide suitable tubular screen operating rods 64 one of which is slidably engaged with the lower portion of the tubes 8 of the outer members 2 of the side bars of the screen frame. The tubular rods 64 are projected up into and entirely inclosed in the tubes 8 when the screen frame is in a lowered or inoperative position and when said screen is raised the rods 64 are automatically retracted from or held down while the screen is raised and when the screen has been raised in the usual manner to the height of the lower bar of the open inner sash and cannot in this manner be further raised the rods 64 are automatically locked in their projected positions and may be grasped by suitable handles 65 formed by inwardly extending lugs on the lower ends of the rods and said rods employed to further push the screen frame upwardly to an out of the way position above the window sashes.

The locking mechanism for holding the screen operating rods 64 projected, comprises bolts 66 which are slidably mounted in tubular casings 67 which in turn are secured in the outer ends of the tube 8 on the lower cross bar of the screen frame as shown. The bolts 66 are projected and yieldingly held in a projected position by coiled spring 68 arranged between the inner end of the bolts and the closed inner ends of the casings 67. The outward movement of the bolts by the springs 68 is limited by studs 69 secured in the bolts and engaged with slots 70 in the casings as shown. The bolts 66 when projected from the casings 67 also project beyond the ends of the tube 8 and are adapted to engage apertures 71 in the inner sides of the upper ends of the tubular operating rods 64 when the latter are projected from the tubes 8 on the side bars of the screen frame thereby locking said rods in their projected positions to permit the same to be employed for raising the screen frame in the manner described.

In order to retract the bolts 66 to permit the operating rods 64 to be retracted into the tubes on the side bars of the window frame, I provide bolt retracting plungers 72 one of which is slidably mounted in each of the rods 64 below the holes 71 therein. The plungers 72 have their upper ends beveled on their inner sides to engage the projecting

ends of the bolts 66 so that when the plungers are forced upwardly the bolts 66 will be pushed back in their casings against the pressure of their springs 68. The plungers 72 have secured thereto operating rods 73 which extend downwardly through the tubular screen operating rods and project a slight distance below the lower ends of said rods 64 so that when the screen frame is lowered the projecting ends of the rods 73 will be brought into engagement with the window sill and said rods and the plungers 72 thus forced upwardly in the rods 64 thereby bringing the beveled upper ends of the plungers into engagement with the ends of the bolts 66 and retracting the latter in the manner described. The plunger operating rods 73 are retracted or forced downwardly as soon as the screen frame is raised and the outer ends of the rods disengaged from the window sill, by means of coiled springs 74 which are arranged on said rods between stop collars 75 secured in the tubular rods 64 and combined stop and guide lugs 76 secured in the lower ends of the plunger operating rods 73 as shown. The lugs 76 project beyond one side of the rods 73 and engage slots 77 in the adjacent side of the screen operating rods 64 and thereby prevent the rods 73 from turning in the tubular rods 64 so that the beveled upper ends of the plungers 72 will always remain in proper position for operative engagement with the projecting ends of the bolts 66. Secured to the outer sides of the lower ends of the plunger operating rods 73 are outwardly curved spring catches 78 which project laterally through notches in the lower ends of the tubes 8 on the side bars 40 of the screens and are adapted to catch into recesses 79 in the lower ends of the screen guides 29 and 30. The engagement of the spring catches 78 with the recesses 79 is sufficient to pull the rods 73 and the tubular screen operating rods 64 downwardly out of the tubes 8 on the screen frame when the latter is raised. The rods 73 and 64 are thus projected or pulled down until the holes 71 in the upper ends of the rods 64 are brought opposite to the bolts 66 which will then be projected into said holes 71 thereby locking the rods in an operative position. When the rods are thus locked a further upward movement of the screen frame will disengage the spring catches 78 from the recesses 79 thus permitting the rods to be carried up with the screen frame. Secured in the upper ends of the rods 64 are pressure springs 64' which are preferably constructed as shown and have their offset loop shaped upper ends in yielding frictional engagement with the inner sides of the outer portions of the tubes 8 whereby the upper ends of the rods 64 will be forced against and held in tight frictional engagement with the oppo-

site sides of the tubes 8 so that the outer ends of the bolts 66 will readily enter the apertures 71 in the rods when said apertures are brought opposite to the bolts.

On the lower ends of the screen guides 29 and 30 are inwardly extending striking lugs 80 with which the lower ends of the plunger operating rods 73 are engaged when the screen frame is pulled down to an open position, said lugs preventing the ends of the rods 73 from marring the window sill. On the upper ends of the screen guides are formed upwardly extending catch lugs 81 which are engaged beneath the lower ends of screen guide extension bars 82 secured to the upper ends of the parting strips on the opposite sides of the window frame, said extension guides forming continuations of the lower guide members to receive the guide shoes of the screen frame when the latter is pushed upwardly to its extreme uppermost position in the window frame. On the upper ends of the extension bars 82 of the screen guides are catch lugs 84 with which the lugs 28 on the spring catches 26 and 27 are engaged when the screen has been pushed to its uppermost position and by means of which the screen is retained in this position. In the lower screen guiding members 29 and 30 at points adjacent to the upper end of the screen frame are locking notches 85 with which the lugs 28 on said spring catches 26 and 27 are engaged when the screen frame is in a full lowered position and whereby the screen will be held down in tight engagement with the window sill and may be manually raised when desired. Secured in the tubes 8 of the side members of the screen are guide keys 8a which engage guide slots 77 in the outer sides of the tubular screen operating rods 64 whereby the latter are prevented from turning in the tubes 8, so that the bolt holes 71 therein will always be in position to receive the bolts 66 when the rods 64 are pulled outwardly from the tubes 8.

In the inner member 1 of the lower cross bar of the window frame are formed recesses 86 which provide hand holds with which the fingers of the hands may be engaged for raising the screen frame until the lower bar thereof is brought adjacent to the lower bar of the inner sash and the operating rods 64 projected to permit the further upward movement of the screen. In said inner member of the lower cross bar of the screen frame is also formed a centrally disposed recess 87 with which is adapted to be engaged the hook shaped upper end of a screen operating rod 88 which may be provided to take the place of the screen operating rods 64 for raising the screen to its extreme upward position or for pulling the same down to a position where the recesses 86 in the lower cross bar thereof may be

reached. The operating rod 88 when not in use is disengaged from the recess 87 and may be kept in any suitable place for use when needed.

5 It will be noted that by providing the spring projected guide shoes for the side bars of the screen frame the latter will slide freely in the window frame and will close tightly against the window sill even though 10 the window frame is not perfectly square or true as the spring projected guide shoes will permit the screen frame to adjust itself to any irregularities of the window frame.

15 From the foregoing description taken in connection with the accompanying drawings, the construction and operation of the invention will be readily understood without requiring a more extended explanation.

20 Various changes in the form, proportion and the minor details of construction may be resorted to without departing from the principle or sacrificing any of the advantages of the invention as claimed.

Having thus described my invention, what 25 I claim is:

1. A window screen of the character described, comprising a frame, guide shoes yieldingly engaged with the side bars of said frame whereby the width of the frame 30 may be slightly increased or diminished to fit between the sides of the window frame, and means to adjust and hold one of said shoes in its adjusted position.

2. A window screen of the character described comprising a frame, guide shoes 35 slidably engaged with the side bars of said frame, springs arranged between said shoes and said side bars whereby the latter are yieldingly held in spaced relation to said 40 bars, a cam link pivotally mounted in one of said side bars, an adjusting rod operatively connected at its lower end with said link, and means connected with said rod whereby the latter is actuated to project and retract 45 said link to operative and inoperative positions for adjusting the position of the shoe operated by said link.

3. A window screen of the character described comprising a frame, guide shoes 50 slidably engaged with the side bars of said frame, springs arranged between said shoes and said guide bars whereby the latter are yieldingly held in spaced relation to said 55 bars, a cam link pivotally mounted in one of said side bars, an adjusting rod operatively connected at its lower end with said link, an adjusting block slidably mounted in one side of said screen frame and connected with said rod, said block having therein a threaded 60 socket, a bearing block fixed in said side of the screen frame, an adjusting screw revolvably mounted in said block and having its inner end engaged with the threaded socket in said adjusting block whereby the latter 65 and said adjusting rod is operated to pro-

ject or retract said cam link to operative and inoperative positions.

4. A window screen of the character described comprising a frame, combined parting strips and screen guiding members secured to the frame of the window and adapted to slidably support said screen whereby the latter may be raised to an inoperative position above the sashes of the window, automatically projected and retracted 70 screen raising rods slidably mounted in the side bars of the screen frame, locking devices to hold said bars in their projected positions and automatically operated means to disengage said locking devices from said bars whereby the latter will be retracted when the screen frame is pulled down to an 75 operative position.

5. A window screen of the character described comprising a frame, casing carried 80 by the side bars of said frame, combined parting strips and screen guiding members secured to the window frame and adapted to slidably support said screen frame whereby the latter may be raised to an inoperative 85 position, tubular screen operating rods slidably mounted in the casings of said side bars of the screen frame, said rods having in their upper ends locking apertures, spring projected bolts adapted to automatically engage said apertures when said operating rods are projected or drawn from 90 said casings on the first upward movement of the screen frame, bolt retracting plungers slidably mounted in said tubular screen operating rods, plunger projecting rods secured to said plungers and extending downwardly below the lower ends of said tubular 95 operating rods whereby when the screen frame is lowered the projecting ends of 100 said rods will engage the window sill and thereby project said plungers into engagement with said locking bolts whereby the latter are retracted to permit said tubular screen operating rods to be pushed upwardly 105 into the casings on the sides of the screen frame when the latter is pulled down to an operative position, and spring catches carried by said plunger operating rods and adapted to be engaged with said screen 110 guides whereby said screen operating rods are projected or drawn to operative position from said casings when the screen frame is raised.

6. A window screen of the character described comprising a frame, combined parting strips and screen guiding members secured to the frame of the window and adapted to slidably support said screen whereby the latter may be raised to an inoperative position above the sashes of the window, said screen guiding members having locking recesses and catch lugs, combined tubular reinforcing members and 120 casings on said screen frame, spring pro- 125

jected guide shoes loosely mounted on the side bars of the screen frame over the tubular casings thereon and having a yielding and sliding engagement with said screen 5 guiding members, spring catches carried by said screen frame and adapted to engage the recesses and catch lugs of said screen guides whereby the screen is held in lowered and raised positions.

10 7. A window screen of the character described comprising a frame, tubular sash parting strips one of which is secured to one side of the window frame, hooks arranged on said strip, a spacing bar secured to the other side of the window frame and having therein slots, a strip engaging hook and lug on said bar adapted to engage said other parting strip whereby the latter is fastened to this side of the window frame, double 20 ended spring catches arranged in said parting strip and having their inner ends engaged with the slots in said spacing bars, hooks secured to the inner sides of said screen guiding bars and adapted to be engaged with the hooks and catches on said parting strips, weather strips secured between and projecting beyond the side edges of said parting strips and screen guides, extension screen guiding members, and

25

means to yieldingly hold said screen frame 30 in sliding engagement with said guiding members.

8. A window screen of the character described comprising a frame having on its outer edges tubular casings, a weather strip 35 comprising a piece of suitable fabric folded lengthwise and having its edges stitched together and inserted into the tubular casing of the upper bar of the screen, a retaining rod inserted between the stitched edges 40 of the strip, whereby the latter is secured in said tubular casing of the upper cross bar of the screen, said strip having its outer folded edge projecting from said casing and in position to engage the outer sash of the 45 window, guide shoes yieldingly engaged with the side bars of the screen frame and adapted to slidably engage the window frame whereby the screen is supported 50

In testimony whereof I have hereunto set my hand in presence of two subscribing witnesses.

CARL GUSTAV MORGNER.
